APPARATUS FOR AUTOMATICALLY
FLUSHING SEWERS

Howard W. Jewell, Los Angeles, Calif.

Application December 5, 1931. Serial No. 579,184

6 Claims. (Cl. 137—106)

This invention relates to means for flushing conduits or receptacles, and particularly to apparatus for automatically flushing such devices at definite predetermined intervals.

5. A broad object of the invention is to automatically suddenly discharge large quantities of water at predetermined intervals.

Another object is to provide a device for storing water derived from a small constant stream 10 until a predetermined amount of water has been accumulated and then automatically suddenly discharging the entire body of stored water, without the use of valves or other elements involving the use of moving parts of metal or other corrodible material.

In order to keep sewers in open condition it is necessary to discharge through them a relatively large amount of water as compared to the amount of solid material handled by the sewer. In some 20 cases the necessary flushing action is produced by admitting a more or less constant stream of water to the sewer at all times. However, in some localities water is scarce and relatively expensive and it is not feasible to constantly admit water 25 to the sewers in streams of sufficient size to keep them clear. It has been found that where the amount of water available is limited it can be much more efficiently utilized for flushing purposes by accumulating it in a reservoir and then 30 suddenly discharging it through the sewer.

An obvious way of flushing sewers is to provide a reservoir into which a small stream of water is constantly admitted and then discharging the water from the reservoir through a float controlled valve whenever it fills. This method however is open to the objection that the valves and other metal parts are subject to corrosion or clogging so that they fail to give reliable service without more or less frequent attention.

40. In accordance with the present invention a tank or reservoir is filled with water from a source of constant flow and is automatically discharged whenever it becomes full, by a siphon. Siphons, of course, have been used before, but a simple siphon is not satisfactory for discharging water from a reservoir for sewer flushing purposes for the reason that it is difficult to suddenly start a flow of water in a siphon of large dimensions. The essential feature of the present invention 45 is a simple means, having no moving parts, for suddenly starting a siphon into action in response to the rise of level of a body of water.

The present invention is an improvement on the invention disclosed and claimed in my copending application, Serial No. 531,135, filed April 18, 1931.

The invention will be readily understood from the following detailed description read in connection with the accompanying drawing, in which:

Figure 1 is an elevational view of the invention shown installed in a manhole; and

Figure 2 is a detail sectional view of a metering valve as disclosed in Figure 1.

Figure 3 is a detail view showing a modified form of a portion of the invention as disclosed in Figure 1.

Referring to Figure 1, a manhole 1 is shown positioned adjacent a sewer line 2 which is to be periodically flushed. The manhole is provided with a neck 3 positioned just below the surface of the ground and adapted to be closed by the usual cover plate 4. The manhole chamber proper, which is positioned below the neck opening 3, is preferably constructed of concrete as shown, and is enlarged laterally below the neck to provide a reservoir 5 of suitable dimensions to hold sufficient water for flushing purposes. The floor of the reservoir 5 may be constructed in part of concrete as shown at 6 and in part of wooden flooring as shown at 7. The exact shape and construction of the storage reservoir 5 is of course immaterial.

To discharge the contents of the reservoir 5 into the sewer 2, a siphon designated generally at 8 is provided. This siphon comprises an upper inverted U-section 9, and a lower U-section 10 connecting through an elbow 11 with the sewer 2. The upper and lower U-sections are shown connected by a straight pipe 12. The parts of the siphon 8 are all preferably constructed of vitrified clay or similar watertight, non-corrodible material, and the joints between the different sections are necessarily made fluid tight.

Mounted on the uppermost part of siphon 8 is an open tubular member 13 which is joined to the siphon by a water-tight connection. Within the tubular member 13 and connected to the interior of the siphon 8, is a tube 14 which extends upwardly from the siphon, then downwardly and upwardly, forming a U-section, and then again downwardly as illustrated. The dimensions of the tube 14 may be varied under different operating conditions, but I have found that a tube of half-inch internal diameter produces satisfactory results. A small hole 15 of about one-eighth inch diameter is provided in the U-section of tube 14 as shown in the drawing, and an opening 16 is provided in the wall of the tubular member 13.

For supplying a constant small stream of water to the manhole, a pipe 17 having a metering nozzle

zle 18 in the end thereof is brought into the manhole from a source of supply such as the usual city water system. The nozzle 18 is positioned to discharge into the tubular member 13 as shown. Nozzle 18 may be of any desired construction, but I have found that the particular type of valve shown is imminently satisfactory.

Referring to Figure 2, this nozzle comprises an outer tubular member 19 threaded at its top for connection to a pipe fitting 20, and threaded at its bottom to receive a plug 21. Plug 21 has a tapered inner end rising to a conical point 22 and is provided with a longitudinal passage 23 leading therethrough.

15 The main portion of passage 23 may be relatively large, for instance it may have a diameter of approximately one-thirty-second of an inch. The quantity of water delivered by the nozzle is determined by the diameter of the upper end 20 of passage 23 which is usually very small; for instance, it may be of the size produced by a number 60 drill, although the actual size will depend in each case on the quantity of water desired to be delivered. Metering nozzles of the 25 type described, having a very small aperture to deliver a very small stream of water, are easily clogged by any sediment that may be in the water supply, and I have found that a nozzle having a conical tip 22 as shown, with the discharge 30 aperture in the tip of the cone, is relatively free from this trouble for the reason that any sediment entering the nozzle body from the pipe 17 tends to settle about the base of the conical plug and will not ordinarily lodge against the 35 small discharge opening in the tip of the cone.

The device described operates as follows:

Assume, to begin with, that the lower U-section 10 of the siphon is filled with water to the level indicated by the dotted line 24 and that a 40 small trickle of water is constantly flowing from the metering nozzle 18. This water flows into the tubular member 13, which will hereafter be termed the auxiliary reservoir. When the water fills the auxiliary reservoir to the level of the 45 aperture 15 it flows into the tube 14 and thereafter the level of the water in the auxiliary reservoir and the tube 14 rises until it overflows from the tube 14 into the reservoir 5.

It should be noted that the aperture 16 in the 50 auxiliary reservoir is positioned slightly higher than the bend 25 in tube 14 so that the level of the water in the auxiliary reservoir will not ordinarily rise to the level of aperture 16.

Water will continue to flow from the nozzle 55 18 into the auxiliary reservoir 13 and thence out through the tube 14 into the reservoir 5, thus gradually filling the latter. Up until the time when the water reaches the level indicated by line 26, the interior of the siphon 8 is in communication with the air in the reservoir 5 through the sniff hole 27 in the member 9. Therefore the air within the siphon is at atmospheric pressure and the level of the water in tube section 28 will be the same as that in tube 60 section 29, the latter being filled up to the overflow bend 25. However, when the water level in the reservoir 5 rises above the sniff hole 27, the air is compressed within the siphon by the hydrostatic pressure of the water in the reservoir. 65 This pressure gradually increases and forces water into the elbow 9 so that by the time the reservoir 5 has been filled to the level indicated by dotted line 30, the hydrostatic pressure created forces the water up into the elbow 9 substantially to the overflow level indicated by

dotted line 31. This rise of water into the elbow 9 compresses the air in the siphon, which pressure forces the water level in the lower U-section down substantially to the level indicated by the dotted line 32, some water being forced out of the 80 mouth of the elbow 10 into the sewer 2.

The increase of pressure in the siphon 9 likewise forces the level of the water down in the tube section 28. The distance between the levels 85 24 and 32 in the siphon, and the length of section 29 are preferably made substantially equal, so that the water level in tube 28 is forced down almost to the bottom of this tube.

It will be seen from the above description that 90 when the water level in the main reservoir 5 reaches the discharge end of tube 14, water is about ready to flow through the siphon 8. If no special means were provided for suddenly setting the siphon into action, continued rising of the water level in reservoir 5 would cause a slow 95 trickle of water to flow over the rim of the section 9 and thence out through the siphon. However, under these conditions, the main body of the siphon 8 comprising the tube 12 would not 100 fill completely with water and no siphon action would be set up. It is necessary in order to start the siphon action to remove most or all of the air from the main portion of the siphon, either by discharging it through the tube 14 or by carrying it out into the sewer 2 by an initial 105 rush of water.

In accordance with the present invention, the siphon is set into action by suddenly discharging air from the siphon through tube 14 just before or after the water in reservoir 5 touches the 110 discharge end of tube 14. There are at least two ways in which the rising water level may cause the sudden release of air from the siphon through the tube 14, and I may utilize either or both of these modes of operation. They will therefore 115 be described separately.

It will be observed that when the water rises to the level 31 in the upper siphon member 9 and forces the water level in the lower U-section 10 from level 24 down to level 32, the air in the 120 siphon 8 is placed under pressure and that this pressure will force the level of water in the section 28 of tube 14 below the level of the water in section 29, the upper level in the latter section being limited by the overflow at bend 25. The 125 length of tube section 29 is preferably made slightly less than the distance between the levels 24 and 32 in the main siphon. Therefore, when the reservoir has been filled approximately to the level 30, the water in tube section 28 will 130 be forced almost to the bottom of this section. A slight additional increase in the head of the water in the reservoir 5 will increase the air pressure in the siphon sufficiently to force the water level in section 28 below the bend into section 135 29. It will be seen that the upper end of the water column in tube section 29 cannot become higher than the bend 25. Therefore, after all the water is forced out of section 28 into 29, the height of the water column in section 29 is reduced below that necessary to counterbalance the air pressure in the siphon. This results in the water column in tube section 29 being suddenly 140 discharged over the bend 25, permitting the air to rush from the siphon 8 out through tube 14, 145 being discharged from the end of tube 14 and also through the aperture 15. This sudden release of the air in the siphon permits a sudden rush of water from the reservoir 5 into the siphon and this rush of water carries any remaining air 150

out of the siphon into the sewer 2, thus filling the siphon with water, which thereafter quickly empties the reservoir 5 by its siphon action.

In the second mode of operation, the discharge 5 of water in section 29 of tube 14 is produced by setting up a siphon action in the end section 33 of the tube 14 when the surface of the water in reservoir 5 rises and contacts with the end of the tube. Ordinarily, water admitted through the 10 metering nozzle 18 into the auxiliary reservoir 13 flows slowly through the aperture 15 in tube section 29 and thence over the bend 25 and down through tube section 33 where it discharges into the main reservoir. This flow of water over the 15 bend 25 is of insufficient volume to fill the tube section 33, but merely trickles through the tube. Because of the fact that tube section 33 is not completely filled with water, no siphon action is produced. However, I have found that with 20 the proper ratios of water flow to the diameter of tube 14, when the level of the water in the main reservoir 5 rises to and seals the end of tube 14, it, for some reason, operates to discharge the column of water in tube section 29, thus permitting the discharge of air from the siphon as 25 previously described. The reason for this discharge taking place when, and only when, the lower end of the tube 14 is sealed by the rising water level in the reservoir 5, is not clearly understood by me. It may be that the water trickling down section 33 of tube 14 entraps and carries with it some air, this air returning to the tube after the passage of water globule so long as the end of the tube is open, thus preventing 30 any material reduction of the pressure in the tube 14 at bend 25. However, it may be that when the end of the tube is sealed by the rising water level in the reservoir 5, it is impossible for air to return after leaving the tube, and as a result 35 the air is partially or completely exhausted from the tube which is then sufficiently sealed with water to set up the siphon action. Whatever the theory of operation, I have found by repeated tests that with certain determined ratios of volume of water flow to the diameter of tube 14, 40 that the discharge will unfailingly occur at or shortly after the time at which the rising water level in reservoir 5 seals the end of the tube even though the air pressure in the main siphon 9 is 45 by itself not sufficient to discharge the water from tube section 29.

After the main siphon 8 has been set into action by the discharge of the air therefrom through tube 14, it rapidly siphons the water from the 50 reservoir 5 into the sewer 2 until the level of the water in the reservoir drops to the snif hole 27 in the upper siphon section 9. As soon as the level drops below the snif hole 27, air is admitted therethrough into the siphon, which air displaces 55 the water in the siphon and stops the siphon action. The small snif hole 27 however stops the siphon action gradually, so that the lower U-section 10 is left filled with water to the level 24. This leaves the entire device in the condition described at the commencement of its operation, so 60 that the reservoir 5 is again filled by the trickle of water from the metering nozzle 18 which falls into the auxiliary reservoir 13, flows through the aperture 15 into the tube 14 and thence out over the bend 25 and through the discharge section 33 into the main reservoir.

It is important to note that although at the moment the siphon is set into action the air therein is discharged outwardly through tube 14, 65 air cannot freely return through this tube after

the siphon action has started and the pressure is reduced below atmospheric, for the reason that the auxiliary reservoir 13 is filled with water to the level of the bend 25 and this water flows through the aperture 15 into the tube 14, thus at least partly filling this tube with water and preventing any rapid suction of air through the tube that might enter through the lower open end of section 33.

It is to be understood that the entire time required for the siphon 8 to empty the reservoir 5 is only a fraction of a minute and this time is insufficient to empty the auxiliary reservoir 13, through the aperture 15.

Although the proportions of the flushing system may be varied to fit varying needs I have found that a system operates with perfect satisfaction in which the reservoir 5 has a capacity of about 300 gallons, the siphon 8 is about eight inches in diameter, the distance between levels 24 and 32 is about twelve inches, the length of tube section 29 is ten inches, the distance from aperture 15 to bend 25 is five inches, the diameter of tube 14 is half an inch, and the discharge end of tube 14 is positioned about twelve inches above the overflow level 31 of the upper bend 9.

Since the siphon is set into action in response to the rise of the water level in the main reservoir to a predetermined height, the frequency of discharge of the device may be varied by changing the rate of admission of water to the reservoir through the metering nozzle 18. The rate of flow through the metering valve may be readily altered by using plugs 21 having apertures 22 of different desired sizes.

The flushing system described is practical because it has no mechanically moving parts and can be constructed of cheap materials that are resistive to corrosion and the operation of which will not be interfered with by the gases to which all severs are more or less exposed.

In actual service the system has been found to function regularly without fail over long periods of time.

Various modifications of the system described above in connection with Figure 1 may be made.

One possible modification has been illustrated in Figure 3, in which the structure of the entire device is exactly the same as disclosed in Figure 1, except that the single tube 14 has been eliminated and two separate tubes 37 and 39 substituted therefor. The parts of the structure disclosed in Figure 3, that are the same as those of Figure 1, are designated with the same reference numerals with the addition of the suffix "a".

The embodiment disclosed in Figure 3, operates as follows:

Water trickles from a metering valve, not shown, into the open tubular member 13a, until the latter is filled to the level of the bend in tube 37, after which it trickles out through tube 37 precisely as described in connection with Figure 1. While the main reservoir 5 is empty the pressure in the siphon 9a is substantially atmospheric and water therefore rises in section 40 of tube 39 to the level of the water in the tubular member 13a, which, of course, is determined by the height of the bend in the discharge tube 37. However, as the reservoir 5 fills and the air is compressed in the siphon 9a, the level 140 of the water in section 40 is forced lower and lower until at the time the level of the water in reservoir 5 has risen to the discharge end of tube 37, practically all the water has been forced out of section 40. It is therefore apparent that the 145

pressure head in the siphon 9a is substantially balanced by the pressure head of the column of water in the container 13a.

When the water level in reservoir 5 finally rises to and seals the end of siphon 37 it sets the latter into operation precisely as explained in connection with Figure 1. Siphon 37 therefore rapidly removes water from the tubular member 13a and soon reduces the head of the water above the lower end of section 40 to a value insufficient to counterbalance the pressure in the siphon 9a. The air in the siphon 9a is thereupon immediately and quickly discharged therefrom through tube 39, thus setting the siphon into action precisely as described in Figure 1.

I claim:

1. A flushing device comprising a reservoir, a siphon conduit connecting said reservoir with the container to be flushed, said siphon having its highest point below the top of said reservoir and having an upwardly extending return bend at its discharge end, the height of said return bend being so proportioned that the weight of a column of water therein prevents flow of water through said siphon until the water in said reservoir reaches a predetermined height above the highest part of said siphon, a tube connecting to and extending from the upper portion of said siphon, into said reservoir, said tube having a portion extending upwardly, then downwardly, then upwardly and again downwardly, and discharging into said reservoir approximately at said predetermined level, a container positioned about a portion of said tube comprising at least said last upwardly extending portion, an aperture in the wall of said last upwardly extending portion, and means for supplying water to said container, the length of said last upwardly extending portion being approximately equal to the height of said return bend at the discharge end of said siphon.

2. A flushing device comprising a reservoir, a siphon conduit connecting said reservoir with a container to be flushed, said siphon having its highest point below the top of said reservoir, and having an upwardly extending return bend at its discharge end, the height of said return bend being so proportioned that the weight of a column of water therein prevents flow of water through said siphon until the water in said reservoir reaches a predetermined height above the highest part of said siphon, an auxiliary reservoir, an auxiliary siphon connecting said auxiliary reservoir with said first reservoir and serving as an overflow from the auxiliary reservoir to said first reservoir, the outlet end of said auxiliary siphon projecting downwardly into said main reservoir and being positioned approximately at said predetermined height, a conduit connecting the upper part of said siphon with said auxiliary reservoir and extending downwardly into said auxiliary reservoir a distance below the overflow level therein approximately equal to the height of said return bend at the discharge end of said siphon, means for supplying water to said auxiliary reservoir at a predetermined rate of flow whereby water overflows from said auxiliary reservoir through said auxiliary siphon into said reservoir, the diameter of said auxiliary siphon being so proportioned relative to the rate at which water overflows therethrough that siphon action is set up in said auxiliary siphon when and only when the water in said

reservoir rises to and seals the outlet end of said auxiliary siphon.

3. A flushing device comprising a reservoir, a siphon conduit connecting said reservoir with a container to be flushed, said siphon having its highest point below the top of said reservoir, and having an upwardly extending return bend at its discharge end, the height of said return bend being so proportioned that the weight of a column of water therein prevents flow of water through said siphon until the water in said reservoir reaches a predetermined height above the highest part of said siphon, a tube connected to and extending from the upper portion of said siphon, said tube having a first section extending upwardly from said siphon, a second section extending downwardly, a third section extending upwardly, and a fourth section extending downwardly and discharging into said reservoir approximately at said predetermined level, and means for admitting water to said tube at a point between said first and fourth sections at a predetermined rate.

4. Flushing means comprising a reservoir, means for supplying water thereto, a siphon conduit connecting said reservoir with a container to be flushed, said siphon having an upwardly extending return bend at its discharge end, the height of said return bend being such that the weight of a column of water therein prevents flow of water through said siphon until the water in said reservoir reaches a predetermined height, and means for suddenly releasing air from said siphon in response to the filling of said reservoir approximately to said predetermined height, whereby said siphon suddenly fills with water from said reservoir and thereafter siphons the water from said reservoir, said means for suddenly releasing air from said siphon comprising containing means for containing a column of water of a predetermined maximum height, the means beyond the upper end of the water column being open, and the means beyond the lower end of the water column being connected to the upper part of said siphon; and means other than said siphon conduit for continuously supplying water to said containing means to produce said water column therein.

5. Flushing means comprising a reservoir, means for supplying water thereto, a siphon conduit connecting said reservoir with a container to be flushed, said siphon having an upwardly extending return bend at its discharge end, the height of said return bend being such that the weight of a column of water therein prevents flow of water through said siphon until the water in said reservoir reaches a predetermined height, and means for suddenly releasing air from said siphon in response to the filling of said reservoir approximately to said predetermined height, whereby said siphon suddenly fills with water from said reservoir and thereafter siphons the water from said reservoir, said means for suddenly releasing air from said siphon comprising a tube adapted to contain a column of water of predetermined limited maximum height, the tube beyond the upper end of the water column being open and directed downward within said reservoir, the tube beyond the lower end of the water column being connected to the upper part of said siphon, and means for supplying water to said tube to produce said water column, the downwardly extending end of said open tube being positioned substantially at the upper level of water in said reservoir.

6. A flushing device comprising a reservoir, a siphon conduit connecting said reservoir with the container to be flushed, said siphon having an upwardly extending return bend at its discharge end, the height of said return bend being so proportioned that the weight of a column of water therein prevents flow of water into said siphon until the water in said reservoir reaches a predetermined height above said siphon, a tube connecting to and extending from the upper portion of said siphon, said tube having a portion ex-

tending upwardly, then downwardly, then upwardly, and being open at the end beyond said last upwardly extending portion, a container positioned about a portion of said tube comprising at least said last upwardly extending portion, an aperture in the wall of said last upwardly extending portion, and means for continuously supplying water to said container whereby water is continuously supplied to said tube through said aperture.
